UNITED STATES PATENT OFFICE

126,071

DESIGN FOR AN AMPLIFIER CONSOLE

Arthur C. Haggstrom, Rockford, Ill., assigner to
E. H. Scott, Highland Park, Ill.

Application January 2, 1941, Serial No. 97,779

Term of patent 7 years

To all whom it may concern:

Be it known that I, Arthur Chas. Haggstrom, a citizen of the United States, residing in Rockford, in the county of Winnebago, State of Illinois, have invented a new, original, and ornamental Design for an Amplifier Console, of which the following is a specification, reference being had to the accompanying drawing, forming a part thereof.

The single drawing figure is a perspective view of an amplifier console showing my new design.

The rear is plain and the opposite side is like that shown.

I claim:

The ornamental design for an amplifier console, as shown and described.

ARTHUR CHAS. HAGGSTROM,
